(57) CLAIM

The ornamental design for a chair as shown and described.

DESCRIPTION

FIG. 1 is a perspective view of a chair, showing my new design;

FIG. 2 is a front elevation view of the chair shown FIG. 1; FIG. 3 is a rear elevation view of the chair shown in FIG. 1; FIG. 4 is a left side elevation view of the chair shown in FIG. 1, wherein the right side elevation view is a mirror image thereof;

FIG. 5 is a top plan view of the chair shown in FIG. 1; and, FIG. 6 is a bottom plan view of the chair shown in FIG. 1. The broken lines shown in the drawings illustrate portions of the chair that form no part of the claimed design.

1 Claim, 6 Drawing Sheets
